UNITED STATES PATENT OFFICE.

FREDERIC E. MAINE, OF BROOKLYN, NEW YORK.

MOLDING.

SPECIFICATION forming part of Letters Patent No. 769,867, dated September 13, 1904.

Application filed January 23, 1904. Serial No. 190,262. (No model.)

To all whom it may concern:

Be it known that I, FREDERIC E. MAINE, a citizen of the United States, residing in the borough of Brooklyn, city of New York, county 5 of Kings, and State of New York, have invented an Improvement in Moldings, of which the following is a specification.

My invention relates to an improved molding particularly adapted for picture-frames, 10 and the construction of my improved molding is such that when made up into picture-frames the glass, picture, and backing associated therewith may be held within the frame by means secured to and within the rabbet of the molding.

15 In carrying out my invention I employ a molding of any desired shape having a rabbet of usual form provided in one corner thereof, and I also employ a strip of flexible material of appreciable width provided on one 20 side with an adhesive substance, and preferably a narrow strip of suitable material, which, together with the aforesaid strip of flexible material, are secured together and to one face of the rabbet in the molding, as will 25 be hereinafter described.

In the drawings, Figure 1 is a front elevation of a portion of a molding, illustrating my invention; and Figs. 2 and 3 are respectively an edge and rear view of the same. Fig. 4 is 30 a section on line xx , Fig. 1. Fig. 5 is an elevation of a picture-frame; and Fig. 6 is a section on line yy of Fig. 5, showing the accessories employed with the frame constructed of my improved molding.

35 a represents a molding of any desired shape and suitable material provided, as is usual in picture-frame moldings, with a rabbet 2 running longitudinally in one corner thereof.

b is a strip or piece of fabric of suitable 40 flexible material, one surface of which is covered with glue, mucilage, or other adhesive material, and c represents a narrow strip of cardboard or other material which may or may not be approximately of the same width 45 as the depth of the long face of the rabbet in the molding in which a particular strip is to be employed.

One edge of the flexible material b is suitably secured to the long face of the rabbet 2, 50 with the greater portion of the said material

extending beyond the same, and the narrow strip c is suitably fastened in place against the adhesive surface of the material b , with one edge thereof abutting against the short face of the rabbet 2. The flexible material b 55 and strip c may be secured together and to the molding by glue, tacks, or in any other convenient manner.

The molding hereinbefore described may be manufactured and kept in stock and is particularly adapted to be made up into picture-frames in which a glass d , picture-mat e , and a backing f or other accessories may be employed, and the width of the strip c is preferably the same as the combined thickness of 60 the accessories employed in a given frame, as shown in Fig. 6, and does not necessarily correspond with the depth of the rabbet. After these accessories have been placed in position within the frame the flaps or extending portions of the flexible material are to be turned down and made fast to the backing to maintain the accessories in position within the frame, the outer edge of the strip c forming 65 a guide upon which the flexible material is 70 turned down.

In ordinary picture-frames, particularly where the molding is of light weight, the backing which is tacked within the frame forms no support and lends no strength to the frame, 80 which, if large as well as light, tends to bulge at its points of support, and it will be readily apparent that with a frame constructed of my improved molding this difficulty is overcome.

I claim as my invention—

1. As a new article of manufacture, a molding having a rabbet in one corner thereof, a piece of flexible material and a strip of suitable material, said strip and piece of material being secured together and to one face of said 90 rabbet.

2. As a new article of manufacture, a molding having a rabbet running longitudinally of one corner thereof, a piece of flexible material secured to one face of said rabbet and extending beyond the same, and a strip of material secured within the same against the face 95 of the said flexible material.

3. As a new article of manufacture, a picture-frame molding having a rabbet running 100

longitudinally in one corner thereof, a piece of flexible material secured to one face of said rabbet extending beyond the same, and having one surface thereof covered with an adhesive substance, and a strip of material secured therein against the adhesive side of the said flexible material.

4. As a new article of manufacture, a molding having a rabbet in one corner thereof, and

a piece of flexible material secured to one face ¹⁰ of said rabbet, and having one of its sides covered with an adhesive substance.

Signed by me this 6th day of January, 1904.

FREDERIC E. MAINE.
